A. R. TRIST.
FEED WATER REGULATOR FOR STEAM BOILERS AND THE LIKE.
APPLICATION FILED MAY 14, 1912.

UNITED STATES PATENT OFFICE.

ARTHUR RONALD TRIST, OF LONDON, ENGLAND.

FEED-WATER REGULATOR FOR STEAM-BOILERS AND THE LIKE.

1,065,565.

Specification of Letters Patent. Patented June 24, 1913.

Application filed May 14, 1912. Serial No. 697,134.

To all whom it may concern:

Be it known that I, ARTHUR RONALD TRIST, subject of the King of Great Britain and Ireland, residing at Coronation House, 5 4 Lloyd's avenue, in the city of London, England, have invented new and useful Improvements in Feed-Water Regulators for Steam-Boilers and the Like, of which the following is a specification.

10 This invention relates to feed water regulators for steam boilers and the like, of that class in which a float is arranged within a chamber disposed externally to the boiler and is adapted to actuate a valve which in 15 its turn controls the operation of the check valve of the feed pump. In devices of this kind it has been found in practice that considerable difficulty is experienced in initially setting or subsequently varying the apparatus to stop the feed water when the required height of water in the boiler is 20 reached owing to the condensation and heat losses that take place in the steam pipe connecting the steam space of the boiler with the steam space of the regulator thus making it difficult to predetermine their relative altitudes, and that the horizontal disposition of the valves and their seats occasions 25 considerable inconvenience owing to the accumulation of scum or sediment, and the irregular effect of corrosion on the lower sides of the valves and their seats; and further that with such small valves as are used in 30 apparatus of this nature, efficient means of adjusting and locking such valves with certainty and reliability have been impossible 35 to obtain. With my invention all these objectionable features are overcome, and the device while being simple in construction 40 and of low cost to manufacture, permits of the initial setting and subsequent variation of the working level to be obtained in a simple and reliable manner and without disturbing the various necessary connections, 45 thereby permitting adjustments being made while the apparatus is under steam, and in addition to the above enables the whole device to be assembled and the valves adjusted relative to each other and permanently 50 secured in place before leaving the manufacturer's hands. Further I provide means by which the valve arrangements for controlling the steam to the feed check valve operating device are simplified, made more effective in action and by which the replacement

and adjustment of the valves and seatings is facilitated.

In order that the invention may be the better understood I will now proceed to describe the same in relation to the accompanying drawing, reference being had to the letters marked thereon.

My invention consists in providing a valve box *a* having a vertically disposed rod *b* therein, in the cover *c* of the float chamber *d* immediately above the float *e*, the said valve box *a* being adapted to be raised or lowered as desired by means of a threaded part *a'* engaging in a nut *c'* and provided with locking means *f* whereby the said valve box *a* may be fixedly maintained in any desired position within a given range. Owing to the disposition of the valve box *a* any weep, drip or particles of foreign matter are washed down into the float chamber *d* 75 and thence back into the boiler thus avoiding scum and sediment accumulating and clogging the valves *g h*, as obtains with devices having horizontally disposed valves. The said valves *g h* are so disposed that they 80 are a sufficient distance above the water level even when its altitude is increased under the condition of flooded boiler, that they will be rarely if ever submerged, thus cutting of the valves is overcome and the deposition 85 of scum or sediment prevented.

The valves *g h* are combined with a double valve seat *i* as a complete device. The said valve seat *i* is of cylindrical form having recessed ends *j k* and a central hole *l*. 90 At each end of the said hole *l* I form a valve seat and through said hole I dispose a secondary valve stem *m* having the valves *g h* formed or mounted thereon and adapted to bear on the said seat. One or both valves 95 *g h* can be initially separate from the stem *m* in order to assemble the parts but when once assembled the valves *g h* are preferably locked in the stem *m* in a permanent manner to prevent alteration of adjustment being effected by any one. This separate device is disposed between suitably recessed surfaces *n o* drawn together by any suitable means such as a screw thread *p* in order to make a joint around the said device at each 100 end. An annular space *q* is left around the said device between it and the casing in which it is held, and transverse holes *r* are provided in the body *i* of the said device so as to set up communication between the 105 110

space between the valves g h and the annular space g , which latter in turn is connected with a side passage s passing to the device t to be controlled by the steam pressure.

5 The double valve g h is screwed to a connecting rod b attached to the float gear and in order to prevent the double valve g h moving in a rotary direction, the stem is slotted and a transverse pin u is held loosely 10 in the casing, passes loosely through the said slot and thus prevents its rotation but allows it to move longitudinally. The construction is as will be seen from the drawing readily 15 adaptable as part of the screw connecting unions of the device and in this way not only is cost of construction reduced but great facility obtains in getting at the valves and seatings and further a spare double valve g h and seatings i combined can be kept as a 20 complete spare part ready to be put in at a moment's notice as a complete element in a very short time, with great facility and with no necessity for any fine adjustment. The said valves g h or one of them may if desired be 25 supplemented by a choking sleeve or other arrangement adapted to choke the passage past the stem.

The lower end of the rod b is provided 30 with a bridle v or similar device which is adapted to engage with motion reducing mechanism w actuated by the float e . This motion reducing mechanism w is arranged below the valve box a and between it and the float e and consists of a pair of bell crank 35 levers x x the arms of which are of such proportions as to give the necessary reduction of travel of the rod b as compared with the travel of the float e . The said bell crank levers x x are of such a form as to provide 40 two dependent arms and two substantially horizontal, the horizontal arms v' v' engaging with the rod b by means of the before-mentioned bridle v or the like. To the ends of the dependent arms a pair of toggle links 45 y y are pivoted which in turn are adapted to bear or rest upon or are attached to the upper part of the float e . The main pivots z z of the said reducing mechanism w are attached to or mounted in the valve box a or 50 an extension thereof so that during the adjustment of the valve box a relative to the float e the longitudinal relation of rod b and link work w remains undisturbed.

In operation steam is admitted to the upper part of the float chamber d and the water in the boiler to the lower part d' in the usual way; should the water level rise unduly it will lift the float e which pressing upward against the toggle levers z z will 55 draw down the lower valve g off its seat and the upper valve h on to its seat, thus permitting steam from the upper part of the float chamber to pass to the device t controlling 60

the water or feed pump check valve t' through suitable connections in order to cut off the water supply more or less to maintain a substantially constant level. If the level drops the float e will descend more or less in its chamber and allow the link work w to collapse under the action of gravity and the force exerted by the escaping steam upon the valves g h and replace the said lower valve g more or less upon its seat and raise the upper valve h from off its seat thus permitting the steam in the feed pump check valve t' 75 to escape to the atmosphere or condenser.

Having thus fully described my invention, I claim as new and desire to secure by Letters Patent:—

1. In a feed water regulator for steam 80 boilers and the like in combination, a float chamber, a steam control valve box adapted to be concentrically disposed in a vertical position in the upper part of said float chamber, means for adjusting the vertical 85 position of said control valve box relative to the water level, a double valve seat as a separate unit having annular means of discharge through radiating passages from the central passage, clamping means for supporting said seat in a tight manner in said 90 box, a double faced valve adapted to co-act with said double valve seat, a float in said float chamber, operative means mounted on the lower end of said valve box and means 95 for connecting said operative means with said float, substantially as described.

2. In a feed water regulator for steam boilers and the like in combination, a float 100 chamber, a steam control valve box adapted to be concentrically disposed in a vertical position in the upper part of said float chamber, means for adjusting the vertical 105 position of said control valve box relative to the water level, a double valve seat as a 110 separate unit having annular means of discharge through radiating passages from the central passage, clamping means for supporting said seat in a tight manner in said box, a double faced valve having a stem on 115 to which one valve is initially attachable in an adjustable manner and adapted to be locked thereon permanently after adjustment, a float in said float chamber, operative means mounted on the lower end of said valve box and means for connecting said operative means with said float, substantially as described.

In testimony whereof I have signed my name to this specification in the presence of 120 two subscribing witnesses.

ARTHUR RONALD TRIST.
